UNITED STATES PATENT OFFICE.

CHARLES A. CURTIS, OF LOUISVILLE, KENTUCKY.

LEVEL.

1,238,991.

Specification of Letters Patent.

Patented Sept. 4, 1917.

Application filed February 9, 1917. Serial No. 147,519.

To all whom it may concern:

Be it known that I, CHARLES ALBERT CURTIS, a citizen of the United States, residing at Louisville, in the county of Jefferson, State of Kentucky, have invented certain new and useful Improvements in Levels, of which the following is a specification:

This invention relates to levels such as are used by carpenters, machinists, miners and others.

An object of this invention is the provision of a cheap, simple, sensitive, practical and durable device of the character described, which will, when applied to an object indicate any variance from a level or horizontal position and the degree of variance therefrom.

Another object is the provision of a level, which may without adjustment be used upon either horizontal surfaces, or surfaces arranged at any angle to the horizontal.

A further object is the provision of a device adapted to accurately indicate when a surface upon which it may be placed, is level, or plumb, and also to indicate to a degree the angle of the plane of said surface.

A still further object is the provision in a level of the character described of means whereby the indicator may be locked in position permitting a reading to be taken after the level is removed from the surface.

With the foregoing and other objects in view, the invention consists of the novel construction and arrangement of parts illustrated in the accompanying drawing which forms a part of this specification, wherein is set forth an embodiment of the invention, but it is to be understood that such changes and modifications may be resorted to as come within the scope of the appended claims.

In the accompanying drawing, wherein similar reference characters designate like parts in the several views, Fig. 1, is a front elevation of an embodiment of the invention: Fig. 2, a central transverse section of same on an enlarged scale: Fig. 3, a central transverse section of a modification, on an enlarged scale: Fig. 4, a perspective view of the tubular post shown in Fig. 2: Fig. 5, a perspective view of the tubular post shown in Fig. 3.

Referring now in detail to the drawing, the reference character —1— designates a

stock, which may be of usual, or of any desired construction; as illustrated it is provided with one straight edge —2—, but it is to be understood that both edges may be straight edges. The stock is provided with a central chamber —3—, which is closed on one side by a back plate —4— and on the other side by a transparent medium —5— such as glass. A tubular post —6— is extended from the back plate 4 centrally of the chamber. A pendulum, or plumb-bob —7— is mounted on the post 6 and is adapted to swing thereabout through a complete circle. That accurate indications may be had, it is necessary that the bob should swing freely, consequently it is provided with antifriction bearings. In Fig. 2, the antifriction bearings are illustrated as comprising balls —8— positioned respectively between a ball race —9— positioned on the back plate, about the post, a ball race —10— positioned on the post near the forward end thereof, and coöperating ball races —11— in the bore —12— of the hub —14— of the bob. A spirit tube —15— is carried by the bob whereby it may be ascertained if the bob hangs true. The bob is provided with a sight opening —16— through which may be observed degree marks on a scale —17—.

At times it is necessary to use a level in positions where it is difficult to see the scale. To overcome this trouble I have provided means for locking the bob in position so that the reading may be made after the level is removed. As illustrated in Fig. 2,

the locking means comprises a bolt —18— extending through the post and having lateral pins —19— near the forward end which extend through longitudinal slots —20— in the forward end of the post, and are adapted to be brought against the outer ends of the hub 14. The rear end of the bolt 18 is provided with screw threads

—21— on which a thumb lever —22— is mounted. It is obvious that a slight rotary movement of the thumb lever will draw the pins 19 against the hub of the plumb-bob and lock it in position.

The rotary movement of the thumb lever, on the screw thread of the bolt, has a tendency to impart a rotary movement to the bolt, which would be imparted to the plumb-bob by the contact of the pins 19 therewith thereby destroying the accuracy of readings, were it not that rotary movement of the bolt is pre-

vented by reason of the pins 19 being seated in the slots 20 in the forward end of the post 6.

In Fig. 3, I have shown a modified method 5 of mounting and locking the plumb-bob. In this case the tubular post is provided with spaced circumferential ribs, or rings 30— which are narrow and offer very little friction. The post is also provided with a 10 shoulder 31. The bore of the plumb-bob fits properly over the rings 30, and projects beyond the forward end of the post. A bolt 32 is provided on one end with a head 33 which is adapted to be brought 15 to bear against the end of the hub of the bob, and near the other end is provided with a transverse slot 34. A wedge shaped member 35 positioned in the slot 34 bears respectively against the outer surface 20 of the back plate 4 and the end of the slot. It is evident that downward pressure on the wedge will draw the bolt backward and clamp the plumb-bob between the head of the bolt and the shoulder 31 on the post. A 25 spring 36 serves to normally hold the bolt in its forward position with the head of the bolt clear of the hub of the bob. A projection 37 serves to prevent the complete withdrawal of the wedge, and guides 30 may be provided to prevent any lateral movement thereof. The back plate is recessed to accommodate the bolt operating means whereby the level may be laid down flat.

35 It is thought that the mode of operation and the many advantages of my invention may be understood from the foregoing description.

Having thus described my invention so 40 that those skilled in the art pertaining thereto may make and use the same, I claim:

1. A level comprising a chambered stock, a back plate closing said chamber, a tubular post extended into said chamber, a plumb-bob mounted on said post, a spirit level carried by said bob, a scale, the bob having a sight opening through which said

scale may be read, and means extended through said post for locking the bob against 50 movement.

2. A level comprising a chambered stock, a back plate closing said chamber, a tubular post extended into said chamber, a plumb-bob mounted on said post, a spirit level carried by said bob, a scale, the bob having a sight opening through which said scale may be read, a bolt extending through said post, a member extended laterally from said bolt, and means associated with the bolt externally of the chamber and adapted to bring 60 said member into contact with the bob to lock same against movement.

3. A level comprising a chambered stock, a tubular post extended into the chamber, a plumb-bob mounted to swing about said 65 post, a spirit-level carried by said bob, a bolt slidably mounted in said post, means associated with the bolt and adapted to shift it longitudinally, and means connected therewith and adapted to be engaged with the 70 bob to lock it against movement.

4. A level comprising a chambered stock, a back plate, a tubular post extended from said plate into the chamber, a weighted 75 member mounted to swing about said post, a bolt slidably mounted in and extended through said post, a head on said bolt adapted to be engaged with said member, and means associated with the bolt and adapted 80 to actuate same to cause the said head to engage the weighted member and lock it against movement.

5. A level comprising a chambered stock, a back plate, a tubular post extended from 85 said plate into the chamber, a weighted member mounted to swing about said post, a bolt slidably positioned in and extended through said tubular post, a head on said bolt adapted to be engaged with said member, the bolt having a transverse slot near 90 its rear end, a wedge operable in said slot and adapted to slide the bolt backward, and a spring adapted normally to maintain the bolt in its forward position.

CHARLES A. CURTIS.
